United States Patent Office

Des. 196,765
Patented Oct. 29, 1963

196,765

AIRCRAFT

Lawrence B. Rellis, Chicago, Ill.
(9241 N. Olcott, Morton Grove, Ill.)

Filed Dec. 6, 1962, Ser. No. 72,746

Term of patent 14 years

(Cl. D71—1)

FIG. 1 is a front perspective view of an aircraft showing my new design;

FIG. 2 is a top plan view;

FIG. 3 is a side view;

FIG. 4 is a bottom plan view thereof with the landing gear in retracted position;

FIG. 5 is a rear view thereof, and

FIG. 6 is a front view.

I claim:

The ornamental design for an aircraft, as shown.
